Primary Examiner — Elizabeth J Oswecki(74) *Attorney, Agent, or Firm* — Muetting, Raasch & Gebhardt, P.A.(57) **CLAIM**

The ornamental design for a head garment, as shown and described.

DESCRIPTION

FIG. 1 is a perspective view of a head garment, showing our new design, donned on a human head shown in broken lines; FIG. 2 is another perspective view thereof, shown in a closed configuration without a human head shown in broken lines; FIG. 3 is a rear view thereof, in an unwrapped, open configuration;

FIG. 4 is a top view thereof, shown in a closed configuration; FIG. 5 is a left side view thereof;

FIG. 6 is a front side view thereof;

FIG. 7 is a right side view thereof; and,

FIG. 8 is a rear, bottom perspective view thereof.

The broken lines in FIG. 1 of a human head do not form part of the claimed design.
